US0D1078041S

(12) **United States Design Patent** (10) **Patent No.:** **US D1,078,041 S**
(45) **Date of Patent:** **** Jun. 3, 2025**

(54) **GROOVED MANDREL FOR PRODUCING AN EMBOLIC COIL**

(71) Applicants: **NDI Medical Technologies Inc.**, Nisantasi-Istanbul (TR); **NEURAVENTION, INC.**, Buffalo, MN (US)

(72) Inventors: **Civan Islak**, Istanbul (TR); **Sadik Semih Demiralp**, Buffalo, MN (US); **Michael Joseph Kuske**, Waverly, MN (US)

(***) Term: **15 Years**

(21) Appl. No.: **29/852,171**

(22) Filed: **Sep. 2, 2022**

(51) LOC (15) Cl. **24-02**

(52) U.S. Cl.

USPC **D24/133**

(57) **CLAIM**

The ornamental design for a grooved mandrel for producing an embolic coil, as shown and described.

DESCRIPTION

FIG. 1 is a front, top, right side perspective view of a grooved mandrel for producing an embolic coil of the claimed design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

1 Claim, 6 Drawing Sheets
